GEORGE LOOP MOORE AND JAMES ROBERT STEELE, OF OWEGO, NEW YORK.

RAIL ANCHOR.

Application filed March 28, 1927. Serial No. 178,924.

Our invention relates to anchors, that is to say, devices for preventing the longitudinal movement of railway rails.

One of the objects of our invention is 5 to provide a one-piece, self-locking anti-creeper or rail anchor, which will grip the rail with great tenacity, regardless of weather conditions or rail vibrations.

Another object of our invention is to provide an anti-creeper which is easily applied 10 or removed, as the occasion requires.

A further object of our invention is the provision of a rail-anchor so constructed 15 that it may be repeatedly removed and re-placed without impairing its gripping qualities.

The novel features will be more fully understood from the following description and claims taken with the drawings, in 20 which;

Fig. 1 is a transverse sectional view through a rail showing in broken lines one step in applying the rail anchor to a rail, and in full lines, a succeeding step;

Fig. 2 is a transverse sectional view 25 through a rail base showing the rail anchor in place;

Fig. 3 is an end view of the rail anchor, showing same applied to a rail in engagement with the tie;

Fig. 4 is a transverse sectional view 30 through a rail having a modified form of the rail anchor applied thereto.

Referring to the drawing:

The numeral 10 designates a rail which 35 may be of any cross section and which it is desired to hold against any longitudinal creep, and 11 is an underlying tie member forming a stationary part of the road bed and supporting the rail 10.

Our improved rail anchor is made of a 40 single piece of flat metal, preferably of resilient or spring qualities and may be of any desired thickness or width. It comprises an under rail portion 12, having upwardly and inwardly directed hooked end 45 portions 13 and 14 respectively, which are adapted to engage the upper surface of the flanges of the rail when the anchor is in its effective position. The end portion 13 is 50 preferably formed with a single thickness of material, whereas, the end portion 14 is preferably made with a double thickness of material obtained by bending the material

of the jaw portion 14 upon itself or doubling 55 in the manner clearly shown in the drawings, to constitute a curve portion 15, which is contiguous with the inside face of the end portion 14. The curve portion 15 is continued along the upper surface of the under 60 rail portion 12, and in the form shown in Figs. 1 and 2, this extended portion, which is indicated by the numeral 16 is bowed upwardly, as at 17, and its free end 18 bears against the upper face of the under rail portion 12 of the anchor. The aforementioned bowed portion 16, constitutes a spring member 65 adapted to bear against the underside of the rail when the anchor is placed in its effective position on the rail.

In our modified form shown in Fig. 4, the free end 16₁ is normally bent upwardly and obliquely to the upper surface of the under rail portion 12₁ and is slightly bent 70 downwardly with curved portion 18₁, as 75 clearly shown in the figure. In this modification, the extending portion 16₁ functions as a leaf spring, the free end of which is adapted to bear against the underside of the rail, when the anchor is in its effective position on the rail, and, in order to provide a fulcrum point for the spring the under rail portion 12₁ is bowed, as at 19₁ and bears 80 against the underside of portion 16₁ at a point intermediate the free end thereof and 85 its junction with the hooked end portion of the rail anchor.

Referring to Fig. 1, the rail anchor is applied to the rail base, by freely placing the end 13 over the edge of the flange of 90 the rail, bringing the spring bowed portion 16 against the bottom of the rail, as indicated in broken lines. The end 14 is then raised upwardly and at the same time the anchor is moved slightly transversely of 95 the rail by any suitable means, such as, striking the knuckle portion of the end 14 with a hammer until the extending end of the hook engages the upper edge of the rail flange, as indicated in full lines in the 100 figure. This movement places the spring bowed portion 16 under initial compression, thereby causing the end 13 to be brought tightly in contact with the upper surface of the rail flange. The anchor is 105 then driven transversely of the rail by means of a hammer or any suitable implement, to the final position of the device as

shown in Fig. 2. The last mentioned operation causes a still further distortion of the bowed spring portion 16 which exerts a great pressure against the bottom of the rail and causes the device to grip with considerable force the upper surface of the rail base.

The modified form of anchor shown in Fig. 4 is applied in the same manner as that shown in Figs. 1 and 2.

The tendency of the rail creeper to assume its original shape results in an extremely strong gripping action on the rail base and holds it effectively in spite of any rail vibrations, or weather conditions.

The anchor is placed in position so as to abut against the tie, as shown in Fig. 3, at that side of the tie so as to oppose the creeping action of the rail under traffic conditions. Thus, by the engagement with the anchor of the tie the longitudinal movement of the rail is prevented.

It will be seen from the above description that we have devised a rail anchor which can be readily applied to a rail base and can be easily removed by striking the end 13 of the device with a hammer or other suitable tool, and the anchor may be effectively applied again to the rail, if desired, due to the fact that no permanent set has taken place in the metal during its first application, on account of the resiliency of the material from which the anchor is made.

While we have shown our invention in but two forms, it will be obvious to those skilled in the art that it is not so limited, but is susceptible of various other changes and modifications without departing from the spirit thereof, and we desire, therefore, that only such limitations shall be placed thereupon as are imposed by the prior art or as are specifically set forth in the appended claims.

Having thus described our invention what we claim as new and desire to secure by Letters Patent is:

1. A rail anchor comprising an under rail portion, upwardly and inwardly extending hook end portions adapted to engage the upper face of the flange of a rail, and means constituting an extension of one of said hook portions adapted to bear against the underside of the rail base and against said under rail portion, so that when the anchor is driven transversely of the rail to its effective position said means is distorted and by tending to assume its normal condition exerts a strong upward pressure against the base of the rail and a strong downward pressure upon said under rail portion.

2. A single-piece rail anchor comprising an under rail portion, a pair of hook end portions adapted to engage with the upper surface of a rail base, and a spring bar portion

having a free end supported on said under rail portion and adapted to engage the underside of said rail.

3. A single-piece rail anchor comprising an under rail portion, a pair of hook end portions adapted to engage with the upper surface of a rail base, and a spring bar portion bent upwardly from the under rail portion adapted to engage the underside of the rail and having a free end supported on said under rail portion. 75

4. A rail anchor comprising a flat steel bar having at one end a hook portion of single thickness and at its other end a hook portion of double thickness formed by bending the bar upwardly and inwardly, then outwardly upon itself in contiguity with the inside face of the outer layer of material, the free end of the latter hook portion being extended towards the first mentioned hook portion and bent upwardly in the vertical plane of the anchor to constitute a spring member. 80

5. A rail anchor comprising an under rail portion having at each end a hook portion adapted to engage the upper surface of the rail flange, and a resilient member integral with one of said hook end portions and extending over said under rail portion adapted to bear against the underside of the rail and having a free end supported on said under rail portion, whereby when the anchor is applied transversely of the rail base, said resilient member exerts a downward pressure on the anchor and causes a strong gripping action of the hook portions on the rail flanges. 95

6. In a railroad track construction, the combination with a rail of an anchor comprising an under rail portion having the major portion thereof spaced from the undersurface of the rail and provided with hook end portions engaging the upper surface of the rail flange, and a resilient member intermediate the under rail portion and the underside of the rail exerting an upward pressure against said rail at a point intermediate the plane of the web and the region of the flange in contact with one of said hook portions and exerting a downward pressure at a plurality of points on the upper surface of said under rail portion. 100

7. In a railroad track construction, the combination with a rail of an anchor comprising an under rail portion having the major portion thereof spaced from the undersurface of the rail and provided with hook end portions engaging the upper surface of the rail flange, and a bowed resilient portion integral with one of said hook portions extending within said space and exerting a pressure against the underside of said rail. 110

8. A rail anchor comprising an under rail portion having at one end a hook portion of

single thickness and at the other end a hook portion of double thickness, and a resilient bowed member integral with the latter hook portion and supported at its free end on said under rail portion.

9. A single-piece rail anchor comprising an under rail portion adapted to extend transversely of the base of a rail, free thereof and substantially parallel thereto, a hook 10 end of single thickness for engaging the upper surface of the rail flange, a hook end of double thickness for engaging the upper surface of the rail flange and a resilient element in continuation of the inside portion of 15 the hook end of doubled thickness adapted to contact with the underside of a rail at a point intermediate the medial vertical transverse plane of the under rail portion and the vertical plane of the free end of one of said 20 hook portions so that upon hooking one of the hook ends about the flange of a rail the other hook end may be raised vertically

and transversely of the rail to engage about the other flange of the rail and cause the resilient element to exert an upward pressure 25 against the underside of the rail to secure the anchor effectively upon the rail.

10. A single-piece anchor formed of flat steel and having an under rail portion, a curved member of single thickness for engaging 30 one of the flanges of a rail, a curved member of double thickness for engaging the other flange of a rail, and a resilient member continuous with the member of double thickness and bearing against said under rail portion at a plurality of points and 35 adapted to exert a pressure against the underside of the rail when the anchor is mounted in its operative position.

In testimony whereof we hereunto affix 40 our signatures.

GEORGE LOOP MOORE.
JAMES ROBERT STEELE.
